FORCEPS

Ralph O. Christensen, Edina, Minn.

Application March 29, 1948, Serial No. 17,631

1 Claim. (Cl. 32—62)

1

This invention relates to an improved forceps for extracting teeth of people.

An object of the present invention is to provide certain new and useful improvements whereby the forceps may be conveniently manipulated in one hand thus leaving the other hand free to do other things necessary to attend to the needs of a dental patient.

Another object of the invention is to provide a maximum pressing action of the jaws of the forceps with a minimum of power applied to the handles.

A still further object of the invention is to provide forceps, the jaws of which will engage a tooth with sufficient gripping surface so that the tooth will be easily extracted from the jaw of a patient.

A still further object of the invention is to simplify the construction and operation of forceps, and to construct and change the parts in such a manner as to produce a very strong and durable forceps.

With these and other objects in view, the present invention consists in the combination and arrangement of parts, as will be hereinafter more fully described, shown in the accompanying drawings and particularly pointed out in the appended claim, it being understood that changes in the form, proportion, and size may be made, within the scope of the claim, without departing from the spirit of the invention.

Figure 1 is a view in side elevation of the novel forceps in its closed position.

Figure 2 is a view in side elevation of the novel forceps in its open position.

Figure 3 is a sectional view on line 3—3 of Figure 2 looking in the direction of the arrows.

Figure 4 is a sectional view of the movable and fixed jaws of the forceps shown in Figure 1, disclosing the longitudinal curved groove in each of the jaws.

Like characters of reference indicate corresponding parts in each of the several figures of the drawings.

The forceps 10 includes a handle 12 terminating in a stationary jaw 14.

An ear 16 projects from the inner face of the handle 12 intermediate its end while a second ear 18 projects from the inner face of handle 12 adjacent a fixed or stationary jaw 14. A second handle 20 shorter than handle 12 is formed with bifurcations 24 and 26. The bifurcations 24 and 26 straddle the ear 16 and a pivot pin 28 extends through apertures in the bifurcations 24 and 26 and the ear 16 to pivotally mount the handle

20 to the handle 12 intermediate its ends. An extension 22 on handle 20 extends beyond the pivot or fulcrum 28 for handles 12 and 20. A movable jaw 30 is provided with bifurcations at 34 which straddle the ear 18 on handle 12 and a pivot pin 36 extends through apertures in the bifurcations and ear 18 for pivotally mounting the jaw 30 on the handle 12 opposite the fixed jaw 14 on handle 12. A link 38 connects the extension 22 of handle 20 which extends beyond the pivot or fulcrum 28 and the rear portion of the movable jaw 30.

The jaws 14 and 30 are normally held in their open position by means of a spring 40 disposed longitudinally between the inside face of the handles 12 and 20 in the rear of the pivotal connection 28 between the handles 12 and 20, see Figure 2 of the drawings. The forceps 10 can be manipulated without employment of the spring 40 and the spring 40 is generally eliminated as an element of the forceps 10.

The jaws 14 and 30 are each provided with a longitudinal curved groove 42 which extends from the tip end of the jaws 14 and 30 to the recessed portions 44 and 46 formed in the handle 12 and in the movable jaw 30 respectively.

When the handle 20 is moved upwardly (see Figure 1) the handle 20 pivots about its fulcrum 28 and extension 22 moves downwardly toward the handle 12. When the extension 22 of handle 20 is moved toward the handle 12, link 38 actuates the movable jaw 30 to open position, see Figure 2. When the jaws 14, 30 are separated as shown in Figure 2 of the drawings, the forceps 10 can be inserted in the mouth of a person and the jaws 14 and 30 can then be moved to engage a tooth by pressing the handle 20 toward the handle 12. The recessed portion 46 in the movable jaw 30 and the recessed portion 44 in the handle 12 being opposite each other provide space between the jaws for the upper enlarged portion of a tooth and at the same time permit the jaws 14 and 30 to engage the tooth at the exact position for quick and satisfactory extraction of the tooth from a person's jaw.

The forceps disclosed in Figures 1 and 2 of the drawings is used for the extraction of the upper anterior teeth. It is my intention to provide a set of six forceps which would be utilized for the extraction of the different teeth from the jaws of a person. Since the teeth of a person are positioned at different angles in the jaw with respect to the mouth, it will be necessary to utilize different shaped and length jaws with the six forceps so that all the teeth can be easily extracted from

the jaws of a person. There are forceps each for the upper anterior teeth, upper bi-cuspid teeth, lower anterior and bi-cuspid teeth, lower molars, upper right molars, and upper left molars.

The curved longitudinal groove 42 in the movable jaw 30 and the fixed jaw 14 will fit the curvature of the teeth to permit a large gripping surface to engage a tooth which will facilitate the extraction of a tooth.

The forceps while utilizing the link connection 38 which connects the extension 22 of handle 20 extending beyond the fulcrum 28 of the handles 12 and 20 with the rear portion of the pivotal or movable jaw 30 produces a toggle motion to force the movable jaw 30 toward the stationary jaw 14 with great power which insures an efficient and easy extraction of teeth from the jaws of patients.

Therefore, it is believed that I have devised forceps for the extraction of teeth in which a very powerful force can be obtained by the manipulation of one hand.

What is claimed is:

Forceps comprising a pair of levers of different lengths pivotally interconnected at respectively intermediate points thereof, each lever having a hand-gripping rear portion, a fixed jaw integrally formed on the forward end portion of the longer

of said levers and disposed a substantial distance forwardly of the lever pivot, the shorter lever terminating at its forward end in slightly spaced relation to the lever pivot, a movable jaw pivoted on said longer lever intermediate the forward end thereof and the lever pivot point, and having a laterally outwardly extending portion to form a bellcrank, and a toggle link pivotally connected at one end to said outwardly disposed portion of said movable jaw and pivotally connected at its other end to the forward end of the shorter lever, to form the sole means for actuating said movable jaw, all of said pivots being completely restricted against any rectilinear movement whatever.
